Apollos Richmond of Providence R. I.

Assign to

A. B. Barstow & co. of Providence aforesaid
Letters Patent No. 719. - Dated August 14th 1855 -

The Schedule referred to in these Letters Patent, and making part of the same.

To all persons to whom these presents shall come.

Be it known, that I Apollos

Richmond of Providence, in the County of Providence, and State of Rhode Island, have produced a new and original design for a cooking stove, which I denominate the "Harp," and I hereby declare that the said new design is fully described and represented in the following specification and accompanying drawings,

In plate 1. Fig 1. is a view of the side plate of the stove, and fig 2. a section of the same, taken in the plane of the line A, B. Fig 1.

In plate 2. Fig 3. is a view of the bottom plate.

In plate 3 Fig 4. is a view of one of the front plates, and fig 5 is a section of the same taken in the plane of the line C, D.

In plate 4. Fig 6. is an elevation of another of the front plates and Fig 7. a section of the same taken in the plane of the line E, F.

The side plate Fig's 1. & 2. plate 1. is ornamented on its lower portion with raised figures of harps or ancient lyres, a, a, a, &c. The long panel b, b, is ornamented with similar harps a, a. The square panel c, c, has around it the mouldings d, d, &c. the scolloped moulding e, e. and in its center one harp a. The small door f, f. of this plate is ornamented in a similar manner, as is also the oven door g, g. which has in its center a large harp or lyre.

The bottom plate Fig 3. plate 2. has ornamented mouldings around it and the scolloped moulding e, e. The front plate 3. Fig 4. has in its lower corners the harps a, a, and is ornamented with two panels i, i, i, i, having mouldings d, d, &c. and the scolloped mouldings e, e. The other front plate, plate 4. Fig 7. in the same manner as the door f, f. of the side plate.

Having thus described my new design I shall state my

Claim as follows

What I claim as my production and desire to have secured to me by Letters Patent, is the new design for a cooking stove, consisting of the ornamental, plain and sculptured mouldings d. d. & e. e. and figures of harps or ancient lyres, as herein above described, and represented in the Drawings.
